UNITED STATES PATENT OFFICE

RICHARD T. GRIFFITHS, OF AKRON, OHIO, ASSIGNOR TO THE MILLER RUBBER COMPANY, OF AKRON, OHIO, A CORPORATION OF OHIO.

PACKING GASKET AND METHOD OF MAKING SAME.

Original application filed August 25, 1927, Serial No. 215,438. Divided and this application filed August 25, 1928. Serial No. 302,970.

My present invention relates to an improved packing gasket, and includes matter divided out of an application filed by me in the U. S. Patent Office on the 25th day of 5 August, 1927, Serial Number 215,438.

This invention aims to provide a novel packing gasket of sponge rubber having homogeneously united attaching means to enable the strip to be readily attached to a 10 carrying plate such as a door facing or jamb, and includes the novel article hereinafter described and defined by the appended claims.

In order that the invention may be better 15 understood, reference is made to the accompanying drawings in which:

Fig. 1 is a perspective view showing a portion of a refrigerator door (by way of example) and the manner in which my improved packing strip is applied thereto.

Fig. 2 is a transverse section through the strip on a line with one of the attaching devices.

Fig. 3 is a sectional view showing the 25 manner of applying the strip.

Fig. 4 is a fragmentary section of mold showing the method of forming the strip.

Fig. 4^a is a transverse section thereof.

Fig. 5 is a perspective view of one of the 30 discs used to form the attaching means.

Fig. 6 is a sectional detail of a modified form of attaching means.

Fig. 7 is a similar view of a further modification.

Fig. 8 is a still further modification.

Figs. 9 and 10 are detail views illustrating the method of manufacturing the article of Fig. 7, and

Fig. 11 is a detail view illustrating the 40 method of making the article of Fig. 8.

Referring by reference characters to this drawing, the numeral 1 designates a closure member of the swinging type such as a metal refrigerator door having the flange portion

45 1^a to which the packing strip is to be secured. This is provided with a plurality of holes 1^b spaced apart distances according to circumstances or as may be found most desirable.

50 2 designates the packing strip or gasket of sponge rubber and most desirably made of semi-cylindrical shape.

At distances corresponding to the spacing of the holes 1^b, the flat face of the gasket is

provided with attaching devices in the shape 55 of buttons or projections, each comprising a shank 3 of solid soft rubber and a diameter corresponding approximately to the diameter of opening 1^b, and enlarged head or flange 3^a of a flexible character. Given such a 60 construction, I have found that by the use of a suitable tool such as indicated at 4, the strip including its attaching means may be so distorted from normal condition as to allow the flexible flange 3^a to be poked or 65 pushed through the opening 1^b whereupon its inherent resilience will cause it to draw the flat face of the gasket into contact with the carrying plate and hold it firmly in position.

70 I have found that by making the attaching members of hollow form as shown in Fig. 3, the connection above described is facilitated. Such construction aids in economical manufacture by the following 75 method which I have devised.

In Fig. 4, I have shown conventionally and in fragmentary form a three part mold comprising a lower or main member 8 having a mold cavity 8^a of a shape conforming 80 to the shape of the desired packing strip or gasket, a top member 7 and an intermediate member 6 having an opening therethrough the lower portion 6^a of which is of a diameter corresponding to the diameter of the 85 stem 3 of the attaching member while the upper part 6^b is countersunk or of a diameter corresponding to the head 3^a of said attaching member. A length of unvulcanized sponge rubber compound of a size insufficient to fill the cavity 8^a is placed 90 therein, mold member 6 applied, and a disc 3^x of unvulcanized or partially vulcanized soft solid rubber compound (see Figs. 4^a and 5), is placed in the rebated or counter- 95 sunk portion 6^b after which the top plate 7 is applied and the mold subjected to heat in the customary manner.

The heat softens the rubber disc which tends to sag into the opening and be pressed 100 further therein by air or gases entrapped above the disc. As the heat is continued the sponge rubber compound expands by reason of the blower therein until it fills the mold cavity and contacts with the de- 105 pressed portion of the disc or discs and the sponge rubber strip and cupped disc members are by the further heat vulcanized to-

gether into a single unitary or homogeneous article of the shape shown in Figs. 1 and 2.

Instead of making the button or attaching means of hollow form as above described, I may make it solid as indicated at 3^b, Fig. 6. In this form, I prefer to partially vulcanize the attaching portions 3^b before placing them in the mold. The rubber of this and the 10 sponge rubber strip are so compounded that by the time the sponge rubber strip is vulcanized, the cure of the attaching members will be completed. If desired, the attaching means may be of spear head shape in cross 15 section as indicated at 3^c, Fig. 7 having a hollow interior.

In order to manufacture a gasket strip according to this figure, I provide a three part mold as shown in Fig. 9 comprising top, 20 bottom, and intermediate plates 9, 10, and 11, respectively, having a mold cavity of the shape of the attaching member or button and having a core pin 11 carried by the upper plate and depending into the cavity, it being 25 understood of course that in practice the mold would have a large number of such cavities for molding a plurality of articles in a single operation.

Sufficient rubber having been placed in 30 each cavity to just fill the same when the mold is closed, the closed mold is subjected to sufficient heat to partially vulcanize the button or buttons, whereafter the mold plate 11 is removed and placed between the mold 35 plates 12 and 13, the latter having a mold cavity 13^a corresponding to the cavity 10^a while the plate 12 has a cavity 12^a corresponding to the desired shape of gasket strip.

The mold being subjected to proper heat, 40 the sponge rubber compound shown in the cavity expands and contacts with and surrounds the base flange of the button and projects part way into the hollow shank and is firmly united thereto.

45 As a further modification, I may make

the gasket strip and attaching means all of sponge rubber as indicated at 3^d, Fig. 8, which may be accomplished by placing in the gasket cavity 14^a of mold member 14 sufficient sponge rubber compound to cause 50 the rubber to be forced into the recesses which form the attaching members, said recesses being of the proper shape as indicated in connection with Fig. 7. It will be understood that the mold vulcanization produces a skin on the sponge rubber which gives requisite strength, but further strength or stiffness may be imparted to the attaching means by molding therein a reinforce such as a tack *d* placed in the mold cavity and 55 surrounded by the sponge rubber as it expands.

If desired, the mold of Fig. 9 may be a separate mold from that of Fig. 10 as an 60 entirety, with the button forming cavities set closely together to increase capacity and the buttons thereafter transferred to another plate 11, Fig. 10, with the holes spaced apart the proper distance for gasket attachment.

Having thus described my invention, what 70 I claim is:

1. A packing gasket comprising a strip of cellular rubber having relatively stiff rubber attaching buttons homogeneously united thereto. 75

2. A packing gasket comprising an elongated strip of cellular rubber having an imperforate skin and a plurality of relatively stiff rubber attaching buttons homogeneously united thereto. 80

3. A packing gasket comprising an elongated strip of cellular rubber having a plurality of buttons of solid soft rubber homogeneously united thereto.

4. A packing gasket of cellular rubber 85 having a continuous imperforate skin surface and a plurality of attaching buttons of cellular soft rubber homogeneously united thereto, said buttons having hollow shanks.

RICHARD T. GRIFFITHS.
